FOOT VALVE

Leo D. Hill, Bryan, Ohio, assignor to The Aro Equipment Corporation, Bryan, Ohio, a corporation of Ohio

Application April 26, 1946, Serial No. 665,096

9 Claims. (Cl. 103—229)

1

This invention relates to foot valves and particularly to foot valves for use in a pump for pumping materials, for example, grease, lubricating oil, or the like from a closed container or drum.

Many grease or lubricant containers are provided with pumps and meters for pumping and measuring the amount of lubricant delivered, on which a charge or record is based. In some prior devices, it was possible, when the lubricant level became low, for air to be pumped with lubricant, which air passed through the meter and resulted in a false reading thereof. Various schemes have been devised to prevent such an occurrence, but they are all too complicated and cumbersome, or were not 100 per cent effective.

It is, therefore, an object of the invention to provide an improved device for preventing air from passing through the meter in apparatus of the type described.

It is also an object of the invention to provide an improved foot valve construction for a pump for delivering liquid from a container.

It is also an object of the invention to provide an improved foot valve for preventing the pumping of air with the liquid delivered from a container which is compact, inexpensive and completely effective under all conditions, including changes in the viscosity or specific gravity of liquids which may be placed in the container.

It is a further object of the invention to provide an improved float operated lock for a foot valve of the type described, and to prevent turbulence from affecting the operation of the float valve while insuring that the float valve closely follows the liquid level in the container.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is an elevational view of the container and apparatus for delivering a metered amount of fluid through a flexible hose connection;

Figure 2 is a vertical view, partially in section, of the pump, metering valve, connections and a portion of the tank used in the apparatus shown in Figure 1;

Figure 3 is an enlarged vertical sectional view of the foot valve shown in Figure 2;

Figure 4 is a horizontal sectional view taken on line 4—4 of Figure 3;

Figure 5 is a sectional view taken on line 5—5 of Figure 3;

2

Figure 6 is a sectional view taken on line 6—6 of Figure 6;

Figure 7 is a side elevational view of the pivoted leverage mechanism shown in Fig. 3;

Figure 8 is a top view of the leverage mechanism shown in Figure 7;

Figure 9 is a side view of the leverage mechanism shown in Figure 7;

Figure 10 is an enlarged detail view of the pivot for the leverage mechanism; and

Figure 11 is a view similar to Figure 3, with the foot valve plate shown in the blocked open position.

Referring specifically to the drawing for a detailed description of the invention, as shown in Figures 1 and 2, numeral 11 designates generally a closed tank or container for lubricant or other liquid. A pump assembly for the liquid, generally indicated at 12 is inclosed within the container 11 and a casing at the top of the container. Liquid delivered by the pump passes through a metering device 13 to which is connected a flexible delivery hose 14 provided with a shut-off nozzle 15.

As best shown in Figure 2, the pump comprises an air operated driving motor 16 and a pump 17 for fluid in the container 11. The air operated driving motor 16 comprises a piston 18 reciprocable in a cylinder 19. Air pressure from a suitable source operates the air motor 16 through a valve mechanism (not shown). The piston 18 reciprocates a large connecting rod 21 which extends through packing 22 into a pressure chamber 23, a lower end 24 of the connecting rod 21 providing for pumping fluid from the pressure chamber 23. The air pump is standard equipment and forms no part of the present invention, it being obvious that any means for reciprocating connecting rod 21, mechanical, electrical, or manual may be utilized.

The connecting rod 21 is secured to a smaller connecting rod 25 which has a piston 26 for pumping liquid at its lower extremity. The lower connecting rod 25 passes through a packing 27 in the pressure chamber 23. A cylinder 28 for the liquid piston 26 extends downwardly in the container 11 and has a foot valve assembly generally indicated at 29 secured at its lower extremity by a threaded collar 31. A partition 32 having ports 33 therein for the passage of liquid extends across the cylinder 28 below the piston 26 on its lowest down stroke position. The piston 26 is provided with a pancake valve 34, biased toward the closed position by a spring 35. The piston has liquid passages or ports 30 therethrough and the opera-

tion of the liquid pump up to this point is well understood in the art.

Referring now to Figures 2 to 10 inclusive for a description of the novel features of the invention, the foot valve assembly 28 comprises a foot valve plate 36 which seats on a land 37 formed on the top of the collar 31. The collar 31 is provided with ports 38 and a central boss 39 having a central opening 41 therethrough. A guide pin, generally indicated at 42 extends through the central opening 41 in boss 39 and is secured to the foot valve plate 36 by a reduced portion 43 which is flattened at 44 at its upper end.

The guide pin 42 is preferably round in cross section, and is provided with a hexagonal washer 45 intermediate its ends and below the boss 39. Below the hexagonal washer 45 the pin 42 is machined to provide two conical shaped portions 46 and 47 with a depending reduced portion 48. The conical-shaped portions thereby form outwardly sloped surfaces 49 and 51 and horizontal shoulders 52, 53 and 54. A vertical surface 55 on the guide pin 42 is provided between the hexagonal washer 45 and the uppermost horizontal shoulder 52.

A depending skirt 40 is secured to collar 31 by rolling at 50 into an annular recess 50a, and the skirt 40 extends to within a few inches of the bottom of container 11, as shown in Figure 2. The skirt is provided at its lower end with sufficient openings 50b to permit the free flow of the liquid in the container 11 into an annular chamber 56 formed between the lower portion of the skirt 40 and a cylindrical sheet metal member 57 welded to a generally S-shaped annular member 58 which is preferably welded to an intermediate portion of the skirt 40. The S-shaped member 58 provides an annular shoulder 59 disposed in a plane a short distance below the bottom 48 of the guide pin 42.

As best shown in Figures 3 and 5, the shoulder 59 is provided with a small slot 61 through which extends an arm 62 secured to a semi-circular strap 63 which is, in turn, welded to a semi-circular hollow float member 64. As shown in Figures 3, 6 and 10, a U-shaped toggle support or float lever lock 65 is preferably soldered to the shoulder 59 below the slot 61 and provides a loose pivotal support for the arm 62, strap 63 and float 64, which may be conveniently referred to generally as a float valve mechanism 66.

The toggle support 65 pivotally supports the float valve assembly 66 in the following manner. The arm 62 is provided with a vertically extending portion 67, which is the portion that extends through slot 61 in shoulder 59, and with a portion 68 bent at an angle of about 40° from the vertical. The vertical portion 67 of arm 62 is provided with opposed cut-outs or slots 69 which engage arms 71 of the V-shaped float lever lock 65. The float 64, therefore, moves the bent portion 68 in an arc denoted by the dotted arrow in Figure 3 when the level of liquid in the container 11 rises or falls, it being obvious that the movement of float 64 and arm 68 are closely limited by the shape of the float lever lock 65 and the size of the cut-outs 69.

Vent openings 72 are provided adjacent the upper part of chamber 56 so that any air entrapped accidentally in chamber 56 may readily escape and find its way to the air space above the liquid in the container 11. In Figure 3, the dot and dash line indicates one possible liquid level, and the dot and dash line in Figure 11

indicates a condition wherein the liquid level has fallen to the point where the foot valve plate 36 is blocked open.

It will also be noted that the end of angularly bent arm 68 is beveled at 73, for a purpose hereinafter described.

Operation

The device described above operates in the following manner. As the air pump 16 is operated by the action of compressed air on the air piston 18, the piston 18 is reciprocated and, in turn, reciprocates large connecting rod 21, small connecting rod 25 and fluid delivery piston 26. Assuming that the pump has been in operation, on the upstroke thereof, the pancake valve 34 on piston 26 is closed, and the fluid present above the piston 26 is forced into the pressure chamber 23 through a suitable check valve (not shown). The large end 24 of connecting rod 21, which also acts as a piston, is being withdrawn from pressure chamber 23 at this time, so that fluid may enter the chamber. At the same time, the foot valve plate 36 is raised by the suction produced beneath the piston 26, and fluid from the container flows into the open bottom of cylindrical member 57 and through the ports 38 in collar 31, thus substantially filling the cylinder 28 below the piston 26.

On the down-stroke of the pump, the foot valve plate 36 is closed by the pressure of the fluid, and the valve plate 34 of piston 26 is opened against the bias of spring 35, so that the fluid in the cylinder 28 passes through the ports 38 in the piston 26. At the same time, the piston end 24 of the connecting rod 21 descends in pressure chamber 23, the check valve hereinbefore referred to is closed, and fluid under pressure is delivered to the meter 13, line 14 and nozzle 15, through a conduit 74, as shown best in Figure 2.

The fluid in the container 11 fills the float chamber 56 through inlets 50b, but it is to be noted that the float 64 is in a quiescent zone and is not subject to the flow or turbulence of the fluid being pumped. So long as the liquid level in the container is above a predetermined level, where there is no likelihood of air passing through the pump and meter, the float maintains the angular arm 68 in the position shown in Figures 2 and 3, where it cannot interfere with the operation of the foot valve 36.

As soon as the liquid drops to the level shown in Figure 11, however, the float 64 drops and pivots the angular arm 68 about the member 65, thus moving the end 73 of the arm 68 first into contact with the vertical surface 55 of the foot valve guide pin 42. On the next up-stroke of the pump, the end 73 of arm 68 will slide under and engage either shoulder 52, 53 or 54, depending on the viscosity of the fluid being pumped, since the heavier oils, for example, raise the foot valve plate 36 higher on each stroke of the pump than a light oil. The liquid level at which the foot valve plate 36 is thus blocked is sufficiently high to insure that no air enters the pump and passes through the meter 13.

When the foot valve plate 36 is blocked open, it will be obvious that the pumping of liquid is stopped, since the piston valve plate 34 is no longer lifted on the down-stroke against the force of the spring 35, and liquid is merely forced back and forth through the ports 38 in collar 31.

Although a considerable amount of liquid is left in the container 11, it is not wasted, as the

container is generally refilled. When this occurs, the float 64 is again raised and the beveled edge 73 of arm 68 readily disengages from the shoulder on the guide pin 42 and the arm 68 resumes the position shown in Figures 2 and 3, thus dropping the foot valve plate 36 onto its seat 37 and permitting normal operation of the pumping mechanism.

While I have herein shown and described a preferred embodiment of my invention, manifestly it is susceptible of modification and rearrangement of the parts without departing from the spirit and scope thereof. I do not, therefore, wish to be understood as limiting my invention to the precise form herein disclosed, except as I may be so limited by the appended claims.

I claim as my invention:

1. A foot valve construction for a pump for delivering liquids from a container comprising a foot valve plate, a member providing a seat for said foot valve plate, a slidable support affording reciprocating movement of said foot valve plate to opened and closed positions with respect to said seat, means for blocking said foot valve plate in opened position and for again unblocking said foot valve plate, said means comprising a float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism directly beneath said foot valve plate and substantially within the confines of the downwardly projected area of said seat member in a float chamber below said foot valve, said chamber being substantially totally enclosed so that unusual disturbances in the liquid will not be transmitted in any appreciable degree to the liquid which is in contact with said float, ports in said chamber permitting entrance of the liquid into said chamber, the inner vertical bounding surface of the chamber forming a liquid inlet passage, another of the bounding surfaces of said chamber being a horizontal wall, said pivoted leverage mechanism and float being pivoted from a point on said horizontal wall, and said float and said pivot point being laterally spaced to permit upward and downward movement of the float in an arc within said float chamber and to provide arcuate movement of said arm into and out of blocking position.

2. A foot valve construction for a pump for delivering liquids from a container comprising a foot valve plate, a member providing a seat for said foot valve plate, a slidable support affording reciprocating movement of said foot valve plate to opened and closed positions with respect to said seat, means for blocking said foot valve plate in opened position and for again unblocking said foot valve plate, said means comprising a float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism directly beneath said foot valve plate

and substantially within the confines of the downwardly projected area of said seat member in a float chamber below said foot valve, said chamber being bounded by two separate vertical continuous surfaces disposed one within the other, said chamber being of considerably greater cross section height than cross section width, a horizontal wall bounding the chamber at the top end, the other end of said chamber being ported to the liquid, the said pivoted leverage mechanism and float being pivoted from a point on said horizontal wall, and said float and said pivot point being laterally spaced on substantially opposite sides of the axis of the inner vertical surface bounding said chamber to permit upward and downward movement of the float in an arc within said float chamber and to provide arcuate movement of said arm into and out of blocking position.

3. A foot valve construction for a pump for delivering liquids from a container comprising a foot valve plate, a member providing a seat for said foot valve plate, a slidable support affording reciprocating movement of said foot valve plate to opened and closed positions with respect to said seat, means for blocking said foot valve plate in opened position and for again unblocking said foot valve plate, said means comprising a float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism directly beneath said foot valve plate and substantially within the confines of the downwardly projected area of said seat member in a float chamber below said foot valve, said chamber being bounded by two separate vertical continuous surfaces disposed one within the other, said chamber being of considerably greater cross section height compared to cross section width, a horizontal wall bounding the chamber at the top end, the other end of said chamber being open to the liquid, said pivoted leverage mechanism and float being pivoted from a point on said horizontal wall, said float having a cross section width at least as great as its depth, and said float and said pivot point being laterally spaced on substantially opposite sides of the axis of said inner vertical surface bounding said float chamber to permit upward and downward movement of the float in an arc within said float chamber.

4. A foot valve construction for a pump for delivering liquids from a container comprising a foot valve plate, a member providing a seat for the foot valve plate, a slidable support affording reciprocating movement of said foot valve plate to open and closed positions with respect to said seat, an inlet passage to said foot valve disposed directly beneath said seat member, a horizontal wall extending outwardly from said inlet and supported by said seat member, a float beneath said horizontal wall and outside said inlet, a leverage mechanism operated by said float and having a portion movable when said float reaches a predetermined position to temporarily block said foot valve plate in open position, means for pivotally supporting said float and leverage mechanism from said horizontal wall, said last means comprising a V-shaped

arm secured to said horizontal wall, and slots in said leverage mechanism pivotally engaging said V-shaped arm, said horizontal wall having an aperture therein through which a portion of said leverage mechanism extends.

5. A foot valve construction for a pump for delivering liquids from a container comprising a foot valve plate, a member providing a seat for the foot valve plate, a slidable support affording reciprocating movement of said foot valve plate to open and closed positions with respect to said seat, an inlet passage to said foot valve disposed directly beneath said seat member, a horizontal wall extending outwardly from said inlet and supported by said seat member, a float beneath said horizontal wall and outside said inlet, a leverage mechanism operated by said float and having a portion movable when said float reaches a predetermined position to temporarily block said foot valve plate in open position, means for pivotally supporting said float and leverage mechanism from said horizontal wall, said last means comprising a V-shaped arm secured to said horizontal wall, and slots in said leverage mechanism pivotally engaging said V-shaped arm, said horizontal wall having an aperture therein through which a portion of said leverage mechanism extends, said V-shaped arms and slots limiting the movement of said float and leverage mechanism.

6. A foot valve construction for a pump for delivering liquids from a container comprising a foot valve plate, a member providing a seat for said foot valve plate, a slidable support affording reciprocating movement of said foot valve plate to opened and closed positions with respect to said seat, means for blocking said foot valve plate in opened position and for again unblocking said foot valve plate, said means comprising a float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism directly beneath said foot valve plate and substantially within the confines of the downwardly projected area of said seat member in an annular chamber below said foot valve, said annular chamber being bounded by two separate vertical continuous surfaces disposed one within the other, said annular chamber being of considerable cross section height compared to cross section width, a horizontal wall bounding the chamber at the top end, said float being positioned within an arcuate portion of said annular chamber, the other end of said chamber being open to the liquid so that a column of liquid is provided beneath the float to prevent the transmission in any appreciable degree of any disturbance to the float from the rest of the liquid, said float and leverage mechanism being pivotally supported from a point on said horizontal wall, said pivot point on said horizontal wall being positioned above the remaining arcuate portion of the annular chamber, whereby the radius of the arc in which said float is permitted to move is as large as possible.

7. A foot valve construction for a pump for delivering liquids from a container comprising a foot valve plate, a member providing a seat for said foot valve plate, a slidable support affording reciprocating movement of said foot

valve plate to opened and closed positions with respect to said seat, means for blocking said foot valve plate in opened position and for again unblocking said foot valve plate, said means comprising a float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism directly beneath said foot valve plate and substantially within the confines of the downwardly projected area of said seat member in an annular chamber below said foot valve, said annular chamber being bounded by two separate vertical cylindrical surfaces disposed one within the other, said chamber being of considerably greater cross section height compared to cross section width, a horizontal wall bounding said annular chamber at the top end, the other end of said annular chamber being open to the liquid, said float and leverage mechanism being pivotally supported from a point on said horizontal wall, said float being positioned within an arcuate portion of said annular chamber, and said pivot point of the leverage mechanism and float being located on said horizontal wall at a position above the remaining arcuate portion of the annular chamber diametrically opposite the center of said float, whereby the radius of the arc in which said float is permitted to move is as large as possible.

8. A foot valve construction for a pump for delivering liquid from a container comprising a foot valve plate, a member providing a seat for said foot valve plate, a slidable support affording reciprocating movement of said foot valve plate to opened and closed positions with respect to said seat, means for blocking said foot valve plate in opened position and for again unblocking said foot valve plate, said means comprising a float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism in an annular chamber, said annular chamber being bounded by two separate vertical cylindrical surfaces disposed one within the other, a horizontal wall bounding said annular chamber at the top end, said float and leverage mechanism being pivotally supported from a point on said horizontal wall, said float being positioned within an arcuate portion of said annular chamber, and the pivot point of said float and leverage mechanism on said horizontal wall being positioned above the remaining arcuate portion of the annular chamber, whereby the radius of the arc in which said float is permitted to move is as large as possible.

9. A foot valve construction for a pump for delivering liquid from a container comprising a foot valve plate, a member providing a seat for said foot valve plate, a slidable support affording reciprocating movement of said foot valve plate to opened and closed positions with respect to said seat, means for blocking said foot valve plate in opened position and for again unblock-

ing said foot valve plate, said means comprising an arcuate float, a pivoted leverage mechanism operated by said float, said pivoted leverage mechanism including an arm movable to a position to block said foot valve plate in the opened position when said float reaches one position and to afford free reciprocating movement of said foot valve plate when said float reaches another position, means for supporting and positioning said float and the leverage mechanism in an annular chamber, said annular chamber being bounded by two separate vertical cylindrical surfaces disposed one within the other, a horizontal wall bounding said annular chamber at the top end, said float and leverage mechanism being pivotally supported from a point on said horizontal wall, said arcuate float being positioned concentrically within a portion of said annular chamber, and the pivot point of said float and leverage mechanism on said horizontal wall being positioned above the remaining arcu-

ate portion of the annular chamber diametrically opposite the center of said arcuate float, whereby the radius of the arc in which said float is permitted to move is as large as possible.
